(57) **CLAIM**

The ornamental design for a thermal cycling system for biological assays, as shown and described.

DESCRIPTION

FIG. 1 is a perspective view of the right, front, and top sides of a thermal cycling system as described herein.

FIG. 2 is a perspective view of the left, back, and bottom sides of a thermal cycling system shown in FIG. 1.

FIG. 3 is a view of the left side of a thermal cycling system shown in FIG. 1.

FIG. 4 is a view of the right side of a thermal cycling system shown in FIG. 1.

FIG. 5 is a view of the top of a thermal cycling system shown in FIG. 1.

FIG. 6 is a view of the bottom of a thermal cycling system shown in FIG. 1.

FIG. 7 is a view of the back of a thermal cycling system shown in FIG. 1; and,

FIG. 8 is a perspective view of the front and the left side of a thermal cycling system shown in FIG. 1 wherein the lid is opened.

The broken lines in FIGS. 2 and 7 are included for the purpose of illustrating portions of the thermal cycling system for biological assays that form no part of the claimed design.
